UNITED STATES PATENT OFFICE

2,610,007

ADJUSTABLE PARACHUTE PACK CONTAINER AND BACK REST

James Martin, Higher Denham, near
Uxbridge, EnglandApplication August 28, 1950, Serial No. 181,749
In Great Britain May 15, 1950

5 Claims. (Cl. 244—122)

1

The present invention relates to improvements in parachute equipment for use in aircraft.

An object of the present invention is to provide an efficient apparatus as hereinafter set forth, which can be readily operated by an airman at will and to suit his requirements.

According to the present invention there is provided a container mounted on an aircraft seat adapted to contain and support the airman's parachute pack while the latter is carried behind his back attached to his harness. The container with the parachute pack forms an adjustable back rest for the airman allowing him readily to adopt a number of seating positions without readjustment of his seat harness while remaining firmly held to his seat against the movements of the aircraft.

Broadly the invention consists of a container for holding a parachute pack carried by the airman attached to his harness, the container being so mounted on an aircraft seat structure and combined with a control actuated by the airman that the container and pack form an adjustable back rest for the airman.

Thus a parachute pack container is attached to the seat structure at its lower end by a hinge connection or the like and at its upper end by a pair of adjustable radius arms the setting of which is controlled by the airman by means of a hand control and control cable run. The airman's shoulder harness straps are attached to shackles or loops mounted on the upper front edge of the container at, or substantially at, the point of attachment of the radius arms, so that the loads from the shoulder straps are transmitted direct to the radius arms and thence to the seat structure. The upward component of the loads is passed down through the container frame to the lower hinges aforesaid.

The invention will now be described in detail, and by way of example, with reference to the accompanying drawings, in which:

Fig. 1 is a side view of the general arrangement.

Fig. 2 is a part front view.

Fig. 3 a sectional side view of radius arms and co-operating parts hereinafter referred to.

Fig. 4 is a section on the line A—A of Fig. 1.

Fig. 5 is a view showing the parachute pack container in relation to the seat structure.

Referring to the drawings, a parachute pack container 1 is attached to the seat structure 2 at its lower end by hinges 3. The container 1 is shaped at its part 4 so as to receive and hold a parachute pack. This pack with the parachute therein is carried on the back of the air-

2

man and is attached to his harness. The container with the pack forms a back rest for the airman. As the container is hinged at 3 it is possible for this to be adjusted to various positions. The airman's shoulder harness straps are attached to shackles 24 mounted on the upper front edge of the container at the point of attachment of radius arms 5 referred to later. Such an attachment allows the loads from the shoulder straps to be transmitted direct to the radius arms and thence to the seat structure. The upward component of the loads is passed down through the container frame to the lower hinges 3. It will be seen from the drawings that the container 1 is a riveted frame-like structure.

A lever 6 is mounted on a cross shaft 7. This latter carries a similar lever at its other end to operate the opposite radius arm. The radius arms 5 each comprise a sliding member 8 and a fixed member 9. The member 9 is pivoted to the seat structure 2 at the radius arm pivot 10. The lever 6 operates a spring loaded latch 11 which engages until withdrawn, in notches 12 and 13 in the sliding member 8. These notches may be of the fixed type as shown at 12 or of the self-return type as shown at 13, or a suitable combination of both.

The lever 6 is actuated by an airman through a cable assembly 14 of any suitable construction. At the end of the cable assembly 14 is an actuating device attached to the seat pan and comprising a hand lever 15, a hand knob 16, a spindle spool 17, an outer spool 18, a coupling 19 and a cover plate 20.

21 is the cable conduit, 22 a stop and 23 clips of the cable assembly.

In the event of an airman desiring a change of seating position, operation of the hand lever 15, through the cable assembly 14 draws down the lever 6 and withdraws the spring loaded latch 11 from one of the notches 12 in the sliding member 8. It will be understood that there are two radius arms, one at each side of the seat structure. The withdrawal of the latches allows the sliding members 8 of the radius arms 5 to move endways in the fixed members 9. As previously mentioned the members 9 are pivoted to the seat structure at 10 so that the members 9 can accommodate themselves to any change in position of the container due to the sliding movement of the members 8.

A slot 25 in the sliding member and a pin 26 in the fixed member prevent complete separation of the two members even should the spring

loaded latch be kept in the disengaged position.

When the spring loaded latch is engaged in a fixed type of notch 12, the airman to move his seating position fore and aft must operate the hand lever, but when the spring loaded latch engages in a self return type of notch 13 he may move his seating position aft, but not forward, without operation of the hand control.

The invention is applicable to most types of aircraft seats in general.

The term "parachute pack container" is intended to include either a parachute or dinghy container.

I claim:

1. In combination with an aircraft seat, a separate container for holding a parachute pack carried by the airman, means for pivoting said container to the seat structure, means for adjusting the container in relation to the seat back, and a control actuated by the airman for operating said adjusting means, the container and pack forming an adjustable back rest for the airman.

2. In combination with an aircraft seat, a separate container for holding a parachute pack carried by the airman, a hinge connection to the seat structure at the lower end of said container, adjustable radius arms connected to the upper end of said container, and a hand actuated control for adjusting said container through said arms in relation to the seat back.

3. In combination with an aircraft seat, a separate adjustable container for holding a parachute pack carried by the airman, means for pivoting the container at its lower end to the seat structure, radius arms comprising fixed members, and sliding members, a pivotal connection for the fixed members to the seat back, a connection for the sliding members to the upper end of said container, a latch device co-operating with said sliding members, and means for operating said latch device for adjusting said container, through said arms, in relation to the seat back.

4. A combined adjustable parachute pack container and back rest for use by an aircraft seat occupant wearing a back parachute pack, means on said container for pivoting this to the seat back, a pair of adjustable radius arms, each of said arms comprising a fixed member pivoted to the seat back, and a sliding member connected to said container, and a control operated by the occupant for moving the sliding members relatively to the fixed members so as to set the container in predetermined positions in relation to the seat back.

5. A combined adjustable parachute pack container and back rest for use by an aircraft seat occupant wearing a back parachute pack, means on said container for pivoting this to the seat back, a pair of adjustable radius arms, each of said arms comprising a fixed member pivoted to the seat back and a sliding member connected to said container, a latch device co-operating with said sliding members, and a hand actuated control for said latch device so that the sliding members can be moved relatively to the fixed members to set the container through said arms at predetermined positions in relation to the back of the seat.

JAMES MARTIN.
